(57) **CLAIM**

The ornamental design for a combination stylus and pen, as shown and described.

DESCRIPTION

FIG. 1 is a perspective view of a combination stylus and pen showing the front and left side of our new design; and, FIG. 2 is an elevation view showing the left side of the combination stylus and pen of FIG. 1. The surfaces or portions of the design not shown in the drawings or described in the specification form no part of the claimed design.
